UNITED STATES PATENT OFFICE.

JOSEPH J. THULL, OF BOYD, WISCONSIN.

DOOR-LATCH.

1,205,061.

Specification of Letters Patent. Patented Nov. 14, 1916.

Application filed April 12, 1916. Serial No. 90,614.

To all whom it may concern:

Be it known that I, JOSEPH J. THULL, a citizen of the United States, residing at Boyd, in the county of Chippewa and State 5 of Wisconsin, have invented certain new and useful Improvements in Door-Latches; and I do hereby desire the following to be a full, clear, and exact description of the invention, such as will enable others skilled 10 in the art to which it appertains to make and use the same.

This invention relates to new and useful improvements in a door latch and one of its objects is the provision of a device of 15 this character, which shall be simple, durable and efficient, and which may be manufactured and sold at a comparatively low cost.

Another object of this invention is to provide a spring pressed bolt slidably secured 20 to the door and normally in an engagement with a keeper and which is capable of being operated to disengage the keeper from either side of the door.

A further object of this invention is to 25 provide a novel means of adjusting the tension of the spring of the sliding bolt to facilitate a correct movement of the sliding bolt into the keeper when the door is in a closed position.

30 A still further object of this invention is to provide an adjustable keeper, which is adapted to be moved away and toward the door as desired.

With these and other objects in view as 35 will become more apparent as the description proceeds, the invention consists in certain novel features of construction, combination and arrangement of parts as will be hereinafter more fully described and 40 claimed.

For a complete understanding of my invention, reference is to be had to the following description and accompanying drawing, in which:—

45 Figure 1 is a fragmentary front elevation of a door, illustrating my invention applied thereto, and Fig. 2 is a longitudinal sectional view, illustrating the means of operating the sliding bolt from either side of the door 50 and also illustrating the means of decreasing and increasing the tension of the spring upon the sliding bolt.

Referring in detail to the drawing, the

numeral 1 indicates a door hinged, to a wall 2 of a building and 3 the jamb of the 55 door. Secured to the door 1 adjacent the opening edge thereof, are a pair of relatively spaced brackets 4, which slidably receive a bolt 5, which has secured thereto a rod 6. The rod 6 extends through the rod 60 5 upon each side thereof and one end of the bolt extends through an elongated slot 7 in the door 1. Secured to each end of the rod 6 are knobs 8, providing means whereby the bolt 5 may be slid within the 65 brackets 4 from either side of the door 1. The bolt 5 is provided with a reduced extension 9 upon one end thereof which is adapted to be slidably received in an adjustable bracket 10 having a recess 11 to 70 receive the extension 9. The adjustable bracket 10 is provided with a reduced extension 13 having an elongated slot 14 for receiving a bolt 15 which extends through the door 1. The bolt 15 has a nut 16 for 75 engaging the reduced extension 14, providing means whereby the adjustable bracket 10 may be moved toward and from the sliding bolt as desired. Mounted upon the reduced extension 9 of the sliding bolt 80 5 is a coil spring 17 and a washer 18. The coil spring 17 is adapted to bear upon the bolt 5 and the collar 18 which engages the end of the adjustable bracket 10 for urging the bolt 5 in the direction of the open end 85 of the door 1 at all times. The free end of the bolt 5 is beveled as indicated at 20 to be received within a keeper 21.

While I have shown and described the preferred embodiment of my invention, it will 90 be understood that minor changes in construction, combination and arrangement of parts may be made without departing from the spirit and scope of the invention as claimed.

Having thus described my invention, what I claim is:—

A door latch comprising a bolt slidably secured to a door, means connected to the bolt for operating said bolt from either side of the door, an extension formed on said bolt, an adjustable bracket provided with a recess in one end thereof to receive the extension, an extension formed on the adjustable bracket and provided with an 100 elongated slot therein, a bolt extending 105

through the slot and door for adjustably securing the adjustable bracket to the door, and a coil spring interposed between the adjustable bracket and the bolt upon the 5 extension of the bolt to urge said bolt into a keeper.

In testimony whereof I affix my signature in presence of two witnesses.

JOSEPH J. THULL.
